SUPPORTING PLATE FOR CHILL MOLDS

Johannes Haag, Neunkirchen, District of Saar,
GermanyApplication June 2, 1937, Serial No. 146,048
In Germany December 10, 1936

6 Claims. (Cl. 22—139)

The object of this invention is to provide a supporting plate for chill molds, comprising a separate wear-resisting plate exposed to the action of the jet of molten metal poured into the mold.

As is known, the consumption of the supporting plates in casting ingots in chill molds has a considerable influence upon the economy of metal manufacture, more particularly in the production of steel. Many suggestions have therefore already been made with a view to diminishing the consumption of supporting plates.

A very useful known supporting plate consists of individual parts, one of which serves as a wear-resisting plate, which is exposed to the direct action of the jet of molten metal, and is therefore subjected to the maximum wear. When the wear has reached a definite stage, only this portion of the supporting plate, which may be referred to as a wear plate, is then exchanged, while the other parts of the supporting plate may remain in use for almost an unlimited time.

Now it has been found that even this composite supporting plate also exhibits disadvantages, which are illustrated in the accompanying dia-

grammatic drawing, in which

Figure 1 is a top plan view of a wear resisting plate of my invention.

Figure 1A is an elevation in section of the plate of Figure 1.

Figure 2 is a top plan view of the plate of Figure 1 after it has become worn through use.

Figure 2A is an elevation in section of the plate of Figure 2.

Figure 3 is a top plan view partly in section illustrating a mold and a wear resisting plate positioned on a support frame.

Figure 4 is a side elevation in section of the apparatus of Figure 3.

The plate 1 has on its under side a projection 2, the main purpose of which is to increase the cross-sectional area of the plate, for the purpose of ensuring it a longer life. In Figure 1 is diagrammatically indicated a hollow 3 in the surface of the plate, such as is soon produced by pouring molten metal into the mold. Now this hollow will become progressively larger and larger, and will finally reach the form shown at 4 in Figure 2. The last casting obtained with this wear plate will indeed still be successful, but if it is used again the next jet of molten metal will break through the weakest point 5 of the plate, so that the molten metal will now escape underneath the wear plate. It will then pass either on to the base plate, or, if the latter

is provided with an aperture, directly into the casting pit, but in any case will lead to very serious disadvantages, the removal of which will involve a great deal of work and heavy expense.

It has appeared hardly possible to prevent the molten metal from breaking through in this way, since the degree of scouring in the wear plate can hardly be ascertained at all, or at least only with great difficulty. If it is desired to obviate such failures thoroughly by renewing the wear plates at the right time, this merely means that the wear plates must be replaced by fresh ones too soon, and consequently at least a portion of the advantage of such composite supporting plates is wasted.

Now the object of the present invention is to provide a simple means for fundamentally preventing the metal from breaking through, without involving an unduly heavy consumption of supporting plates. This aim is attained by providing, between the wear plate and the base plate, an intermediate space filled with fire-proof material.

Further advantages and further features of the invention will be gathered from the ensuing description, in which one example of the invention will be described with reference to Figures 3 and 4 of the accompanying drawing, in which

Figure 3 is a plan of a supporting plate according to the invention, with the chill mold in section on the left-hand side and with the chill mold removed on the right-hand side, and

Figure 4 shows the same in sectional elevation.

A composite supporting plate comprises an actual base plate 5. This is provided, at the places where a chill mold 6 is to be mounted upon it, with a raised portion 7, having a circular recess 8 in the centre. Upon the projecting rim 7 fits an actual wear-resisting plate 9, which has a projection 11 on its under side, which is likewise of circular form and fits into the recess 8 in the base plate 5. The external surface 12 of the projection 7 on the base plate 5 is conical in shape, and is continuous with the external surface 13 of the wear plate 9 which is likewise conical. The base plate 5 and the wear plate 9 are held together by a massive frame 14, which is provided with internally conical side walls 15, the inclination of which corresponds to the conicity of the surfaces 12 and 13. Upon the surface the frame 14 is provided with cam-like projections 16, which enable the chill mold 6 to be accurately centered when lowered from above by a crane on to the wear plate 9. For this

purpose the internal surfaces 17 of the cams 16 are bevelled.

The supporting plate, consisting in all of three parts, namely the base plate, the wear plate and the frame, may also be held together by a wedge or key connection. For this purpose there is provided laterally in the frame 14 a recess 18, which registers with a similar recess located beneath it in the base plate 5. In this recess 10 is inserted a bolt or pin 19, which has a lateral aperture, through which a key or wedge 21 can be passed.

Between the downward projection 11 of the wear plate 9 and the opposite surface of the base plate 5 there is provided according to the invention in the cavity 8 a free space, which is filled with fire-proof material. When, with such a supporting plate, the wear plate is scoured away as far as is indicated in Figure 2, the next casting 20 does not cause the metal to break through, since the fire-proof material which is a poor conductor of heat, opposes the passage of the molten metal in the chill mold until it has solidified. After removal of the chill mold filled with the ingot, 25 the workmen can now see, as soon as the fire-proof material is uncovered, that the wear plate requires to be renewed.

The employment of this invention in practice has shown a substantial improvement in the consumption of supporting plates as compared with even the best of the supporting plates hitherto adopted.

What I claim is:

1. Apparatus for use in casting ingots comprising an ingot mold open at its lower end and a stool upon which said mold is supported, said stool comprising a base plate having a raised formation defining a recess at its upper surface, a wear resisting plate having an integral projection on its bottom surface cooperating with said base plate surface recess to removably seat said wear resisting plate upon said base plate and means for securing said wear resisting plate upon said base plate, said securing means cooperating with said wear resisting plate to support said ingot mold.

2. Apparatus for use in casting ingots comprising an ingot mold open at its lower end and a stool upon which said mold is seated, said stool comprising a base plate having a recess formation at its upper surface, a wear resisting plate having a downwardly projecting portion extending partly within said recess, means for fastening said wear resisting plate to said base plate and a layer of re-enforcing material which is a poor conductor of heat between the projection and the bottom of said recess.

3. Apparatus of the type defined in claim 2 for use in casting ingots wherein said re-enforcing layer is of refractory material.

4. An apparatus for use in casting ingots comprising an ingot mold open at its lower end and a stool on which said mold is seated, said stool comprising a base plate, an annular projection at the upper surface of said plate having a ver-

tically extending inner wall and a tapering outer wall, a removable wear resisting plate resting on the upper surface of said annular projection and provided with a downwardly extending projection in the form of a disc, the portion of said wear resisting plate resting on said annular projection having an outer wall inclined at the same angle as said tapering outer wall of said annular projection, and a ring having a tapering wall fitting said tapering walls of said annular projection and said wear resisting plate.

5. An apparatus for use in casting ingots comprising an ingot mold open at its lower end and a stool on which said mold is seated, said stool comprising a base plate, an annular projection 15 at the upper surface of said plate having a vertically extending inner wall and an upwardly tapering outer wall, a removable wear resisting plate resting on the upper surface of said annular projection, said wear resisting plate being provided with a downwardly extending projection in the form of a disc, the thickness of which is less than the height of said annular projection to form a space between the bottom surrounded by said annular projection and the lower surface 25 of said downwardly extending projection of said wear resisting plate, and refractory material filled in said space, the portion of said wear resisting plate resting on said annular projection having an upwardly tapering outer wall corresponding to the upwardly tapering outer wall of said annular projection, and a ring, having a downwardly tapering wall fitting said upwardly tapering walls of said annular projection and said wear resisting plate.

6. An apparatus for use in casting ingots comprising an ingot mold open at its lower end and a stool on which said mold is seated, said stool comprising a base plate, an annular projection at the upper surface of said plate having a vertically extending inner wall and an upwardly tapering outer wall, a removable wear resisting plate resting on upper surface of said annular projection, said wear resisting plate being provided with a downwardly extending projection 45 in the form of a disc, the thickness of which is less than the height of said annular projection, to form a space between the bottom surrounded by said annular projection and the lower surface of said downwardly extending projection of said wear resisting plate, refractory material in said space, the portion of said wear resisting plate resting on said annular projection having an upwardly tapering outer wall corresponding to the upwardly tapering outer wall of said annular projection, a ring having a downwardly tapering wall fitting said upwardly tapering walls of said annular projection and said wear resisting plate, and cam-like projections on said ring adapted to cooperate with the upwardly tapering outer 55 surface of said mold to guide the latter into its correct position when said mold is being lowered on to the supporting stool.
